UNITED STATES PATENT OFFICE.

SIDNEY D. ANTLE, OF SALISBURY, ILLINOIS.

CAR-COUPING.

SPECIFICATION forming part of Letters Patent No. 295,092, dated March 11, 1884.

Application filed December 15, 1883. (No model.)

To all whom it may concern:

Be it known that I, SIDNEY D. ANTLE, of 5
Salisbury, in the county of Sangamon and
State of Illinois, have invented a new and use-
ful Improvement in Car-Couplings; and I do
hereby declare that the following is a full and
exact description of the same, reference being
had to the accompanying drawings, and to the
letters of reference marked thereon.

10 The object of my improvement in car-cou-
plers is to render the same more certain in op-
eration in the act of coupling two cars to-
gether, and also adapted to couple two cars
15 together certainly where the bumpers are at
different elevations above the ground; and
my invention therein consists in the appa-
ratus employed, and in the combinations of the
various operative parts thereof, all as more
20 fully hereinafter described and claimed.

20 For the better understanding of my im-
provement, reference should be had to the
drawings connected herewith, in which—

Figure 1 is an elevation, partly broken away,
of my car-coupling; and Fig. 2, a top plan
25 view, partly broken away, of the same.

Similar letters denote corresponding parts
in each figure.

A and A' are two draw-heads, and B is a
link of usual form. The draw-head A has
30 slots *a a* in opposite sides, near its front end,
in which a tilting-rod, C, is worked up and
down by means of side bars, D D, to the lower
ends of which the outer ends of the said rod
C are fastened. The center *b* of this rod C is
35 arched upwardly, so as to take between the
sides of the link B and raise its outer end,
when the rod C is raised, which is done by
means of the side bars, D D, which are pivoted
near the top of the draw-bar, as shown
40 at *d*. A cross-bar, E, connects the upper
end of the side bars, D D, and to this a link,
e, is attached, connecting it with a lever, F,
which is pivoted to one end of another cross-
bar, G. When this lever F is moved back, it
45 draws the cross-bar E back and raises the
lower ends of the side bars, D D, which in
turn raise the tilting-rod C, which in turn
raises the link B just as high as may be re-
quired for coupling with the draw-head of
50 another car. A coupling-pin, H, passes down
through the draw-head and holds the link
from coming out of it. In the side of the

draw-head A' there is pivoted a block, I, work-
ing in a proper slot, *h*. This block is thickest
at its center and tapering a little toward its 55
ends. It has a movement on its pivot by
means of a draw-rod, J, passing through an
eye on the end of a cross-bar, K; mounted on
the rear end of the draw-bar. When the
block I is in position directly across the draw- 60
head, its inner end comes directly under the
foot of the pin H, which rests upon it, and
this is the position for coupling. When the
link B enters this draw-head, it strikes the in-
ner end of the block I and pushes it back out 65
of the way, and the pin then falls through the
link. As it has to fall only a short distance,
the coupling is effected with absolute cer-
tainty, and the annoying failures to couple
are thus avoided. To raise this pin out of the 70
link, where great power is frequently required,
and to put it in position, the pin is connected
by a link with one end of a lever, L, pivoted
upon a standard, M, the other end of which
lever is connected by a link, *i*, to one end of 75
another lever, N, pivoted upon a standard, O,
mounted upon the cross-bar K. By this sys-
tem of double levers an enormous power is
exerted upon the pin, so as to withdraw it,
even when the cars are in motion, or to place 80
it in position when required for recoupling.
This pin, as shown, passes through a projec-
tion, *p*, on the top of the draw-head, by which
means the head of the pin is raised, so as to
be in better position for the action of the com- 85
pound levers.

Having thus described my invention, what I
claim as new therein is—

1. The draw-head A, provided with the tilt-
ing-rod C, in combination with the link B, sub- 90
stantially as described.

2. The draw-head A', provided with the
block I, and the compound levers L and N,
substantially as described.

3. The combination of the draw-head A, 95
with its tilting-rod C, and the draw-head A',
with its block I, substantially as described.

This specification signed and witnessed this
27th day of November, 1883.

SIDNEY D. ANTLE.
